UNITED STATES PATENT OFFICE.

ALLAN G. HURDMAN, OF DENVER, COLORADO.

MEANS FOR CONTROLLING THE ESCAPE OF FLUIDS FROM TANKS.

1,070,136.

Specification of Letters Patent. Patented Aug. 12, 1913.

Application filed September 18, 1911. Serial No. 649,880.

To all whom it may concern:

Be it known that I, ALLAN G. HURDMAN, a subject of Great Britain, residing in the city and county of Denver and State of Colorado, have invented certain new and useful Improvements in Means for Controlling the Escape of Fluids from Tanks; and I do declare the following to be a full, clear, and exact description of the invention, such as 10 will enable others skilled in the art to which it appertains, to make and use the same, reference being had to the accompanying drawings, and to the characters of reference marked thereon, which form a part of this 15 specification.

My invention relates to improvements in means for controlling the escape of fluid from tanks.

The particular object which I have in 20 view is to provide a device of this character for controlling the escape of gasoline or other volatile liquid from a tank mounted upon an automobile and employed in connection with the carburetor of an explosive 25 engine.

My improved construction is of such character that the valve to be opened, in order that the liquid may escape, must be operated by the use of a key in connection with a 30 lock of special construction, said lock being located within the tank, but operable from the outside thereof, the lock being of the tumbler variety and of sufficient complexity to make it practically impossible to operate 35 it without the employment of the proper key.

The cylinder or barrel of the lock is arranged to be rotated by the proper key, and this cylinder or barrel is connected with the 40 valve by means of a rod composed of two telescoping members, whose opposite extremities are equipped with universal joints, one of said joints being connected with the cylinder of the lock and the other with the 45 valve, the said valve being provided with a coarse screw, threaded so that the turning of the cylinder by the use of the key will impart the necessary rotary movement to the valve to open or close the same, according to 50 the direction of the rotation of the lock cylinder.

The entire valve and lock mechanisms are concealed within the tank, the cylinder only

of the lock having its outer extremity exposed for the insertion of the key. This 55 makes it practically impossible for an unauthorized person to start the engine of an automobile, for instance, since he is unable to manipulate the lock, and, consequently, unable to open the valve, which allows the 60 gasoline or other volatile liquid to pass to the carburetor in order to form an explosive mixture for the engine carried by the machine.

A further object of the invention is to 65 provide an exceedingly simple and economical construction adapted to efficiently perform the aforesaid function, and to these ends the invention consists of the features 70 hereinafter described, all of which will be fully understood by reference to the accompanying drawing, in which is illustrated an embodiment thereof.

In this drawing: Figure 1 is a vertical section, taken through a tank equipped with my 75 improvement, the lock and valve mechanism being shown in elevation. Fig. 2 is a fragmentary vertical section of the tank, cutting the lock mechanism and illustrating the connection between the cylinder of the lock 80 and the upper extremity of the telescoping rod. Fig. 3 is a similar view of the tank, cutting the valve mechanism and illustrating the connection of the valve piece with the lower extremity of the telescoping rod. 85 Fig. 4 is a similar view, cutting the valve casing, but showing the valve in elevation. Fig. 5 is a horizontal section, taken through the lock on the line 5—5 of Fig. 2.

The same reference characters indicate 90 the same parts in all the views.

Let the numeral 5 designate a tank containing a quantity of volatile liquid 6. This liquid may be gasoline, or any other suitable fluid, adapted for use in forming an 95 explosive mixture for internal combustion engines. Mounted in the bottom of this tank is a valve casing 7, the bottom of the casing being reinforced, as shown at 9, and equipped with legs 8, which are formed integral with a fixture 10, having a flange 12 engaging the bottom of the tank, preferably on the outside, the said fixture in this event being exteriorly located and provided with a perforation 13, whose upper extremity is 105 adapted to form a seat for a valve piece 14,

composed of an exterior member 15 and a member 16 adapted to protrude below the exterior member, the protruding part being fashioned, as shown at 17, to fit the upper 5 extremity of the opening 13, when the valve is in the closed position.

The member 16 of the valve is movable in the exterior member 14 and acted on by a spiral spring 18 located within a recess 19 10 above the member 16 of the valve, whereby the latter is normally held at its outward limit of movement by the action of the spring. The valve member 16 has a shoulder 20, while the lower extremity of the exterior member 15 of the valve is turned inwardly, as shown at 21, below the shoulder 20 to prevent the member 16 from escaping from the valve member 15.

The valve member 15 is provided exteriorly with a coarse screw thread 22, adapted 20 to fit a counterpart thread 23 formed in the valve casing. This thread is of such pitch that a single rotation of the valve will impart a sufficient longitudinal movement to 25 unseat the valve and allow the liquid to pass freely through the perforation 13 of the exteriorly-located fixture 10. The exterior valve member 15 protrudes above the valve casing 7, and is flattened, as shown at 24, 30 and perforated, as shown at 25, to receive a pin 26, which passes through a registering perforation formed in a part 27 pivotally connected, as shown at 27 $\frac{1}{2}$, with the lower extremity of the rod member 28, which is 35 polygonal, preferably square in cross section, and adapted to telescope in a hollow rod member 29 of counterpart shape, thus making the rod, composed of the two members 28 and 29, lengthwise extensible, 40 whereby the said rod is capable of adjustment to harmonize with tanks of various depth.

The two pivot pins 25 and 27 $\frac{1}{2}$ extend at right angles to each other to form a universal joint or coupling. The upper extremity of the telescoping rod member 29 has also a universal joint connection with the lower extremity 30 of the lock cylinder 31, the said cylinder being rotatable in a casing 32 located 45 within the tank and formed integral with a plate 33, which covers an opening 34 formed in the top of the tank and projects beyond the said opening, as shown at 35, there being a shoulder 36, which protrudes centrally into 50 the tank, whereby the plate may be securely fitted, after which it may be brazed or otherwise made fast to the top of the tank in such a manner that it cannot be removed, except by practically destroying the tank. 55 The valve mechanism may be of any suitable ordinary tumbler construction, as, for instance, of the Yale variety of lock. As shown in the drawing, the lock cylinder is equipped with tumbler members 37, which

coöperate with tumbler members 38 located 65 in the valve casing adjacent the opening in which the valve cylinder is located. The tumbler members 38 are acted on by spiral springs 39. The inner extremities of the tumbler members 37 are pointed, as shown 70 at 40, or otherwise suitably fashioned to fit the recesses of a key 41. When the proper key is inserted, the tumbler members 37 will have their outer extremities in exact alinement with the outer surface of the lock cylinder, in which event each pair of tumbler members 37 and 38 will join each other exactly in alinement with the surface of the cylinder and the outer end of the opening in the valve casing, so that, when the proper 80 key is in place, the cylinder may be turned. However, if a key is inserted, which is not shaped to correspond with the tumbler mechanism, one or more of the tumblers 37 or 38 will protrude beyond its normal position, that is, one or more of the tumblers 37 will protrude into a recess in the valve casing, or one or more of the tumblers 38 will protrude into a recess in the lock cylinder, thus making it impossible to rotate the cylinder. As this is an ordinary construction of lock, further detailed explanation is not considered necessary.

The lower extremity 30 of the lock cylinder is reduced in diameter and enters a 95 socket 42 formed in a sleeve 43, which is connected with the lower extremity of the lock cylinder by a pin 44. This sleeve 42 constitutes one of a universal coupling 45, and for this purpose, it terminates in a flattened part 46 connected by means of a pin 47 with a member 48 connected by means of a pin 49 with the upper bifurcated extremity 50 of the telescoping rod member 29. It will be understood that the pivot pins 47 and 49 105 extend at right angles to each other.

In order to form a liquid-tight joint below the lock casing, a stuffing box member 51 is-threaded on the depending part 52 of the casing, a suitable packing 53 being interposed between the stuffing box member 51 and the sleeve 43, said packing being located immediately below the lower depending part of the lock casing. The lock casing is provided, just above the upper extremity of the coupling sleeve or stuffing box member 51, with a reinforcement 54, which is provided with an arch or recess 55 to receive one of a series of lugs 56, formed on the upper extremity of the sleeve 110 51, so that, when the said sleeve is screwed into position, one of the lugs 56 may always be made to register with the recess 55. The said registering lug is then bent sufficiently to cause it to enter the recess 55, whereby 115 the coupling sleeve is positively locked against rotation.

The upper extremity of the valve casing

7 is equipped with a projection 57, which extends upwardly and is interiorly recessed, as shown at 58, intermediate its extremities to receive a pin 59, formed on the upper 5 extremity of the valve member 15. The recess 58 allows the valve member 15 to make a complete rotation, and by the time this is accomplished the pin 58 will be raised sufficiently to bring the upper extremity 60 10 of the projection 57 within the path of the said pin and thus prevent the valve from farther rotary action. The object of this construction is to make it impossible to turn the valve farther than is necessary or sufficient 15 to disengage it from the valve casing.

The exteriorly-located fixture 10, below the perforation 13, is bored, as shown at 61, to form an escape opening for the liquid of the tank to a pipe 62 connected with the 20 fixture 10 by a coupling nut 63. The bore 61 extends inwardly beyond the lower extremity of the opening 13, as shown at 64, whereby, if an attempt is made to unseat the valve by inserting a wire or other device 25 into the bore 61, the said device will pass beyond the lower extremity of the perforation 13, thus making it practically impossible to cause any instrument to pass upwardly through the perforation 13 and 30 unseat the valve.

From the foregoing description, the manner of assembling the mechanism, as well as the use of my improved construction, will be readily understood.

35 As heretofore described, the valve casing 7 and the fixture 10 with its flange 12 are formed integral or cast in a single piece. This integral device, with the valve in place and the lower rod member 28 connected therewith, may be inserted through an opening 65 formed in the bottom of the tank; the flange 12 protruding sufficiently beyond this opening to thoroughly conceal the same 40 and give the necessary support to the fixture 45 10 and valve mechanism. The construction is then secured to the bottom of the tank, as by brazing or other suitable means, the use of screws, however, or other suitable removable fastening devices being avoided. 50 The lock mechanism is then inserted through the opening 34 formed in the top of the tank, together with a telescoping rod member 29, the two rod members 28 and 29 being caused to telescope in operative relation. 55 The flange 35 of the lock casing is secured to the top of the tank in the same manner as the flange 12 of the fixture 10 is secured to the bottom of the tank.

In order to open the valve, it is only 60 necessary to insert the proper key,—see Figs. 1 and 2,—whereby the tumblers 37 and 38 are adjusted to allow the cylinder 31 to turn. A single rotation of this cylinder will impart a corresponding rotary movement to

the valve 14, and this action of the latter 65 will unseat the member 16 of the valve and allow the volatile liquid in the tank to escape to the carburetor, not shown.

As soon as the valve is unseated in the manner heretofore explained, the pin 59 70 will engage the upper extremity 60 of the projection 57 and prevent the further movement of the valve and lock cylinder.

Having thus described my invention, what I claim is:—

1. In means for controlling the discharge of fluid from tanks, the combination with a tank, of a valve mechanism concealed therein and comprising a casing, a valve screw-threaded in the casing, a lock projecting into the tank and equipped with a rotary cylinder, and a connection within the tank between the said cylinder and the said valve, comprising a rod whose extremities are connected by universal joints with both the 85 valve and lock cylinder, substantially as described.

2. The combination with a tank, of valve mechanism located therein and comprising a casing, a valve screw-threaded in the casing, a tumbler lock extending into the tank and including a cylinder rotatably mounted, and a lengthwise adjustable connection between the cylinder and valve within the tank, the opposite extremities of said connection being equipped with universal joints, 90 for the purpose set forth.

3. The combination with a tank, of valve mechanism located therein and including a valve screw-threaded in a suitable casing, 100 a lock extending into the tank including a rotary cylinder, a rod composed of two telescoping members, the said members being respectively connected within the tank by means of universal joints, with the cylinder 105 of the lock and the valve, for the purpose set forth.

4. The combination with a tank, of a valve located therein and including a valve piece lengthwise adjustable within a stationary casing, a lock extending into the tank and including a rotary cylinder, a stuffing box member surrounding the inner extremity of the rotary cylinder within the tank, means for positively locking the said 110 stuffing box member against rotation, and an operative connection between the rotary cylinder and the valve to unseat the latter 115 by the rotation of the cylinder.

5. The combination of a valve adapted to 120 control the flow through the escape orifice of a liquid fuel tank, a longitudinally extensible rod or stem with one end of which the valve is connected, a supporting plate or casing adapted to be secured to the tank in 125 which the other end of the stem is mounted, and means connected with the last mentioned end of the stem for operating and

locking the valve, one extremity of the rod or stem being provided with a universal joint.

6. The combination of a valve adapted to control the flow through the escape orifice of a liquid fuel tank, a longitudinally extensible rod or stem with one end of which the valve is connected, and means connected with the other end of the rod for operating and locking the valve, the said rod

or stem being equipped with a pair of universal joints, one being located near the valve, and the other near the connection at the opposite end of the stem.

In testimony whereof I affix my signature in presence of two witnesses.

ALLAN G. HURDMAN.
